UNITED STATES PATENT OFFICE

HARRY W. DYER, OF NEW YORK, N. Y.

REFRIGERATING APPARATUS

Application filed May 8, 1925. Serial No. 28,963.

This invention relates to refrigerating apparatus of a portable type such as are used in homes and particularly relates to the construction of such apparatus in the arrangement of the cooling chamber, the arrangement of the shelves, the heat insulating of the walls and other details whereby the efficiency of such devices is increased, as more particularly described in the following specification and shown in the accompany drawings, in which, Fig. 1, is an elevation of an ice box constructed according to my invention, Fig. 2, is a sectional elevation corresponding to Fig. 1, Fig. 3 is a transverse cross-section of Fig. 2, Fig. 4 is a detail of one means for securing the sections of the ice box together, Fig. 4^a is a fragmentary plan view, Fig. 5, is an elevation, partly in section, showing the arrangement of shelves, Fig. 6 is a plan view of the shelves, Fig. 7 is a detail in section showing a tray on the shelf, and Fig. 8 shows a circular type of ice box using my invention and including a mechanical refrigerating system.

This invention contemplates an ice box constructed in multiple units which may be increased or decreased as desired. These units are built one upon the other upon matched walls and are securely clamped together. The food or cooling chamber of the ice box is preferably circular in shape with shelves arranged to rotate upon a central shaft or stem. Where the box has a square exterior, the corners are used to house the cooling medium which may be in the form of a triangular tank with a refrigerating coil or a tank of this shape filled with chopped ice. These tanks are preferably of such length as to extend from the top to the bottom of the cooling chamber whereby the refrigerating effect is evenly distributed throughout the cooling chamber. The shelves in the food chamber are detachable and for sanitary reasons are constructed without pockets. The shelves support the food trays which are formed in a segment of a circle to fill the circular shelves. The walls of the ice box are insulated by vacuum tanks enclosed in the wall structure. In the circular type of

ice box the vacuum tank itself forms the walls of the box.

Referring to the drawings, the ice box in Fig. 1 comprises the upper compartment 21 with the door 22 and the lower compartment 24 with the door 25. A cover 23 is applied on top of 21. These compartments are placed over the base 26 which, in the present case, houses the refrigerating mechanism used to cool the compartments 21 and 24.

The walls of the compartments are matched as shown in section in Fig. 2 between the members 27 and 28 enclosing a groove for a rubber gasket 30. The members 27 and 28 are clamped together by the screws 29 at the corners which are preferably located in depressions in the walls so as not to project beyond the plane of the walls. It will be noted that the section 21 may be removed and cover 23 placed on top of section 24, the walls being arranged to match; also it will be noted that any number of sections similar to 21 may be erected one upon the other and clamped together to form a single ice box. This construction in multiple units enables the ice box to be increased or decreased in size with the greatest convenience. The rubber gasket 30 provides an air tight seal between the sections and the groove is arranged in the upper part so that pockets cannot develop in the joint to hold moisture. A removable separating shelf 33 may be provided between the compartments as indicated in Fig. 2.

A wooden ice box of the square type with panelled walls is indicated in the section drawing in Fig. 3. In this case the door 25 is provided with a heat insulating material 31 and a similar heat insulator is provided in the side pockets at 32. The other walls as shown, are heat insulated by the vacuum tanks 151, 152 and 154 enclosed and protected by the paneling of the walls as shown. These tanks are provided with internal spacers 155 to prevent internal collapse due to atmospheric pressure.

Ice boxes constructed according to my invention which have revolving shelves are provided with a central shaft 41 having a cup-shaped bearing 43 at the lower end turn-

ing on the cone 42 on the bottom shelf. The top of this shaft in the upper section is engaged by the sleeve 44 which is rotated by the indexed hand wheel 45 located in a depression on the cover. This enables the shelves of the upper section to be turned to any predetermined position before the door is opened. The top of shaft 41 in the lower sections turns in the cup-shaped depression in shelf 33 as shown.

10 The shaft carries a plurality of radiating arms such as 46 and 47 which support the food trays 48 and 49 in tiers, these trays being removed through the doors by rotating the shaft until they are opposite the doors.

15 Rotating the shelves introduces a tendency to overturn bottles or other utensils placed thereon. To guard against this I provide a skeleton support 50 which may be pivoted on the shaft by a sleeve 51 and which contains a

20 number of perforations 53, 54 and 55 to support utensils such as the milk bottle 52; it is apparent that the part 50 may be shaped to support any object placed on the shelves.

25 The detail construction of the shelves is shown in Figs. 5, 6 and 7. A collar with double flanges 61 and 62 is placed upon a shoulder of the shaft 41. These flanges are perforated to receive the pivots of the bracket arms 63 and in the normal position these arms are radially spaced about the centre shaft. The bracket arms are provided with a separating ridge 65 which acts as a guide for the tray 66 and are provided with 30 perforated lugs 64 which are formed in a depression as shown in section in Fig. 7 to be engaged by the depression 67 of the tray 66. This holds the tray in place so that it cannot move outwards by centrifugal action as the 35 shaft rotates and the depression 67 forms a foot for the tray. The tray 66 is preferably cut away on the side as at 69 so that the contents can easily be seen.

40 Attention is here called to the fact that sanitary requirements prohibits pockets in the construction of devices of this kind where decaying matter might accumulate and for the same reason the parts must readily be disassembled for cleaning purposes. The 45 cone construction supporting the base of the shaft avoids pockets for the accumulation of moisture. The bracket arms are removed by raising up to clear the pivots of the flanges and the collar can be raised on the 50 shaft to clean the place where it seats.

55 The revolving shelves permit of the concentration of articles in the food chamber which are readily accessible and the trays on the shelves form practically a cylinder which 60 prevents the escape of the cold air when the door is opened. In general, it will be observed that the cold air cannot escape to an extent beyond that occupied by a tray which is removed. It is to be noted that the hinged 65 arrangement of the bracket arms enables the

trays and brackets for a segment to be removed, or the trays may be removed and the bracket arms turned to the side as at 63^a, Fig. 8. This provides an enlarged space in the cooling chamber for any special purpose, which is readily convertible as the need may arise.

70 The food chambers are cooled by vertical tanks which, in the case of the square ice box with the round shelves takes advantage

75 of the corner spaces for this purpose as indicated by the tanks 138, 141, 144 and 149, Fig. 3. These tanks are triangular in shape

80 to fit the corners and the outer side may be curved to conform to the contour of the revolving shelves. These tanks extend from

85 the top to the bottom of the compartment as indicated in Fig. 2 and for the ordinary ice box may be filled with ice but in the present construction, which contemplates

88 use of a mechanical refrigerator, refrigerating coils or evaporators 137, 140, 143 and 148 are placed in these tanks and connected by the pipes 139, 142 and 145 and

90 ultimately connected to the refrigerating system hereafter described. These tanks may be filled with brine, water, alcohol or similar

95 fluid which will give up its heat to the refrigerating coil and thereby store and distribute a refrigerating effect at a plurality

98 of points extending throughout the refrigerating chamber. It may be observed at this

100 point that an ice box having a separate compartment filled with ice does not produce a temperature in an adjacent food chamber

105 much below 45° F. With the arrangement shown a more uniform low temperature can be obtained in the food chamber without producing ice in the cooling tanks and the liquid

110 stores the refrigerating effect for a definite interval. The tank 138 when filled with drinking water, may be provided with a draw-off tap at 73 whereby a supply of cold

115 drinking water is available. The same arrangement is shown in Fig. 8 in connection with the cooling tank 141^b which may be

120 filled at 72 and drawn off at 73.

When the ice box is built in sections, each

125 compartment is provided with its own cooling tanks as indicated in Fig. 2. The coils

130 in these tanks may be connected as between 141 and 141^a by the union 91 and a similar connection is made at 91 between tanks 144 and 144^a.

135 When another section is placed upon 21, the caps 92 are removed and connections similar to 91 are used between the

140 tanks.

145 This invention is shown as equipped with a mechanical refrigerating apparatus similar to that disclosed in application, Serial No. 27,071 filed April 30, 1925 in the name of Herman Scharnagel. In this system air is used as the refrigerating medium. The apparatus comprises a motor 17 controlled by a thermostat 159, Fig. 8 which is inserted in

an open ended tube in tank 141^b and connected by wires 156 and 157 and battery 158 with the motor; thus when the temperature of the cooling tank rises above a predetermined value, the circuit of the motor is closed and the mechanism is operated until the temperature of the cooling tank is lowered. The thermostat 159 is also indicated in Figs. 2 and 3. The motor is directly connected to a mechanism 12 comprising the compressor 13 and the expander 14, also the make-up pump 15 and the vacuum pump 16. From the compressor air is led by pipe 131 to the condenser coil 132 and by pipe 134 to the expander 14. From the expander by pipe 136 to the cooling tanks, returning by pipe 146 to the compressor and completing the circuit. The make-up pump 15 is connected to the condenser coil as shown in Fig. 8 and the vacuum pump 16 connects by pipe 114 with the vacuum tanks forming the exterior walls of the cooling chamber. The vacuum tanks may be connected to each other as by the pipe 114^a, Fig. 2. The condenser coil 132 is cooled by the fan 133.

The circular refrigerator shown in Fig. 8 is provided with an annular cooling tank 141^b which forms the interior walls of the cooling chamber. This tank is heat insulated by the vacuum tank 156 which forms the exterior annular walls of the device. These tanks have a sector cut away opposite the door 71. This construction, it will be noted provides a comparatively thin wall and consequently economizes space.

It is observed that in the ordinary square type of ice box a large part of the interior cannot be utilized owing to the need for a free passage across the shelves to make the articles thereon accessible. Even with a free passage, articles are frequently spilled and are troublesome to clean up. By the use of circular shelves the articles thereon can be more concentrated and at the same time readily accessible and when these articles are placed around the centre of revolving shelves each article can be reached by itself without fouling with other articles on the same shelf.

This invention relates to the construction of the refrigerator box and the arrangement of the cooling coils. No novelty is claimed for the refrigerating unit, nor for the refrigerant, which are adapted from the prior art and are referred to herein in a generic sense only. The refrigerating coils 137, 140, 143 and 148 are usually varied in form according to the refrigerant used and these coils are intended to include a full range of equivalent.

Having thus described my invention, I claim:

1. In a refrigerator of the class described, the combination of a plurality of rectangular cooling chambers constructed in multiple

units and forming, when assembled, a continuous cooling chamber, an independent refrigerating element in each unit extending substantially throughout the length of said unit, said elements detachably connected within said cooling chamber and means for circulating a refrigerating medium through each of said independent refrigerating elements. 70

2. In a refrigerator of the class described, the combination of a plurality of similar rectangular chambers without ends with matched, heat insulated walls, means for assembling said units into a continuous vertical cooling chamber, a cover with means for securing the same on the end of the last chamber, a cooling coil in each of said chambers connected to form a continuous vertical cooling coil entirely within said continuous cooling chamber and means for circulating a refrigerating medium through said cooling coil. 75 80 85

3. In a refrigerator of the class described, the combination of a plurality of cooling chambers arranged in multiple units with a door for each unit, said units forming a continuous cooling chamber, a central shaft in each unit, shelves rotatably supported by said shafts and means whereby the shelves in each unit may be rotated independently of each other. 90 95

4. In a refrigerator of the class described, the combination of a plurality of cooling chambers constructed in multiple units with a door for each unit and forming, when assembled, a continuous cooling chamber, a central shaft in each unit having a bearing at the junction of the units and shelves rotatably supported by said shafts. 100

5. In a household refrigerator of the class described, the combination of a plurality of cooling chambers constructed in multiple units and forming, when assembled, a continuous vertical cooling chamber, a vertical refrigerating element in each unit, means connecting the top and bottom of adjacent elements within said cooling chamber and means for circulating a refrigerating medium through each of said refrigerating elements. 105 110

6. In a household refrigerator of the class described, the combination of a plurality of rectangular cooling chambers constructed in multiple units and forming, when assembled, a continuous cooling chamber, an elongated vertical refrigerating element in each unit placed in alignment with each other and operatively connected within said cooling chamber and means for circulating a refrigerating medium through said refrigerating elements. 115 120 125

7. In a household refrigerator of the class described, the combination of a plurality of rectangular cooling chambers constructed in multiple units arranged one above the other and forming, when assembled, a continuous 130

vertical cooling chamber, a vertical refrigerating element in each unit in alignment with each other and operatively connected within said cooling chamber and means for circulating a refrigerating medium through each of said elements.

8. In a refrigerator of the class described, the combination of a cooling chamber constructed of a plurality of similar units arranged in vertical tiers and capable of being varied in size according to the number of units used and a vertically elongated refrigerating element associated with each of said units, said elements being connected together within said cooling chamber.

9. In a refrigerator of the class described, the combination of a cooling chamber constructed of a plurality of similar units arranged in vertical tiers and capable of being varied in size according to the number of units used, a vertical cooling coil in each of said units, said coils having their ends connected between said tiers and extending substantially the length of said units and means for circulating a refrigerating medium through each of said coils.

10. In a portable refrigerator as described, the combination, a housing having a plurality of compartments, one of which contains water and is provided with a spigot outlet and a plurality of cooling elements each comprising an evaporator, one of said evaporators being arranged to cool the water in said compartment, a refrigerating unit in said housing comprising a motor, a pump and a radiator, means connecting said refrigerating unit with said evaporators and a thermostat in one of said compartments controlling the circuit of said motor.

40 11. In a portable refrigerator as described, the combination, a housing having a plurality of cooling elements, said cooling elements each having a refrigerating coil, a water tank in said housing with a draw-off tap for drinking water, one of said coils associated with said water tank to cool said drinking water, a unit comprising a motor, a pump and a radiator, means connecting said pump, radiator and said refrigerating coils in series and 50 a thermostat in said housing automatically controlling the operation of said motor.

Signed at New York, county and State of New York, this 4th day of May, 1925.

HARRY W. DYER.
